MEMO PAPER HOLDER

William H. Burtis, Davis, Calif.

Application September 30, 1938, Serial No. 232,541

3 Claims. (Cl. 281—13)

My invention relates to improvements in a memo paper holder, and it consists of the combinations, constructions and arrangements hereinafter described and claimed.

5 An object of my invention is to provide a memo paper holder in which a single sheet of material is shaped for supporting a paper roll and also for supporting a portion of the paper fed from the roll. The sheet of material is so fashioned 10 that the portion of paper unwound from the roll will be held taut. The free end of the paper is passed under a tear-off bar and the paper is fed from the roll in the opposite direction to that taken while writing on the paper. In other 15 words, any desired amount of paper may be written upon and then the paper can be moved to provide a new writing portion immediately following the written portion. The part of the paper fed through the tear-off bar may be severed from the remaining portion by tearing along the bar.

The device may be supported on the wall or it may be held in the hand. It is possible to design the device to make a pleasing appearance.

25 Other objects and advantages will appear in the following specification, and the novel features of the device will be particularly pointed out in the appended claims.

My invention is illustrated in the accompanying drawing forming a part of this application, in which

Figure 1 is a front elevation of the device;

Figure 2 is a side elevation;

Figure 3 shows a development of the device on a reduced scale;

Figure 4 is a section along the line 4—4 of Figure 1; and

Figure 5 is a development of the tear-off bar.

In carrying out my invention, I provide a holder indicated generally at 1. The holder is preferably made of sheet metal, although it may be formed from a plastic material, if desired. Figure 3 shows the holder 1 provided with a flat writing portion 2 and integral extensions 3. The

45 extensions 3 are bent or curled in the form of a scroll as shown in Figure 2 and also the lower end of the portion 2 is curved to constitute a retainer or cradle for a roll of paper 4. The edge 5 shown in Figure 3, will be positioned at a suffi-

50 ciently high point when the portion 2 is curved to prevent the roll of paper from accidentally moving out of the curved cradle 6. The exten-

55 sions 3 when curled, act as side retaining members and hold the roll against moving longitudinally out of the cradle.

Figure 2 shows the portion 2 as extended at a slight angle with respect to the cradle 6 and the top of the member 1 is bent along a fold-line 7 for causing the portion 8 to lie in a plane that is tangent to the rear of the curved cradle 6. The cradle 6 will therefore rest against a wall 9 or other supporting surface and the portion 8 will contact with the same surface. The device may be supported on the wall by a screw 10 that is inserted through an eyelet 11 in the portion 8.

Although I have shown the extensions 3 and the lower part of the portion 2 fashioned into a scroll, it is obvious that the member 1 may be fashioned into other shapes such as scrolls with straight portions extending at the desired angles to each other. The gist of the invention is the provision of a cradle for a paper roll, this cradle also carrying side members for preventing movement of the roll in the direction of its axis. The top of the member 1 may be shaped in the manner shown at 12 in Figure 1 and it is possible to alter the shape to show angular lines rather than curved lines.

A tear-off bar 13 is shown attached to the member 1. Figure 5 shows a development of the bar and it comprises a strip which is foldable along the dotted lines 14. The strip carries forked ends 15 that have tongues 16 and a recess 17. The inner edge of each recess is spaced from the lines of fold shown at 14. In Figure 3, I show the member 1 provided with openings 18 for receiving the tongues 16. The inner edges of the recesses 17 contact with the member 1 when the tongues are inserted in the openings 18 and this will space the bar 13 a sufficient distance from the member 1 to permit the paper 4 to be passed between the member and the bar. The portions of the tongue projecting through the openings 18 are bent or crimped for holding the tear-off bar in place. It is possible to flex the bar so that its center will contact with the member 1 and this will cause the bar to frictionally engage with the paper that is fed between the bar and the member. It is also possible to provide the bar with a central projection (not shown) that will frictionally engage with the paper. Any means for holding the free end of the paper against the member 1 and permit the paper to be torn along a transverse line 50 will suffice.

From the foregoing description of the various parts of the device, the operation thereof may be readily understood.

The edge 5 is placed far enough from the por-

55

tion 2 to permit a memo paper roll to be readily placed in the cradle 6. The free end of the paper is then passed over the edge 5 and around the outside of the cradle 6, thence over the portion 6 2 and under the tear-off bar 13. Sufficient friction is developed between the paper and the outer surface of the cradle to hold the lower end of the paper taut. The tear-off bar holds the 10 free end of the paper taut. The portion 2 will act as a support for that part of the paper upon 15 which data may be written. A person may write on the paper in the customary manner and as additional paper is needed, the free end of the paper may be pulled, causing the paper to feed 15 under the bar 13. When the writing is completed, the portion of paper thus written upon may be torn along the tear-off bar. It will be seen that the paper can be fed so that new portions will immediately follow the portion written upon.

20 The device is simple enough in construction to be manufactured at low cost and used as an advertising medium. The bar 13 may have advertising matter printed thereon. It is also possible to print advertising matter on the memo 25 paper at spaced intervals and this advertising matter will be periodically brought to the attention of the user as the paper is unwound from the roll.

20 The side edges 19 of the member 1 and the extensions 3 are inclined outwardly and this will cause the scroll formed by the curled extensions to be viewed from the front of the device as shown in Figure 1. The beauty of the device is thus enhanced. The bending of the center of 35 the tear-off bar so that it will frictionally contact with the paper as shown at 13a in Figure 2, leaves sufficient space at both ends of the bar to readily feed the end of the paper under the bar. The feature provided by the upward pull of 40 the paper as against a downward one is important because it allows a continuous list of any desired length to be written before the paper is torn off. The paper itself can carry advertising matter with various products of the company printed 45 across the paper. As the paper is fed through

the device, the names of the products would appear and act as a reminder. The holder can be adapted for use on a desk by adding a suitable support, none being illustrated.

I claim:

1. A memo roll holder comprising a sheet of material having a writing surface and a cradle-shaped end for receiving a roll of writing paper, said end having scroll-shaped extensions that constitute retaining sides for the roll, a paper-gripping and guiding member secured to the opposite end of the sheet, the paper being fed from the roll, around the outer surface of the cradle, over the writing surface of the sheet and under the paper-gripping member, the paper being frictionally gripped at both ends of the writing surface by the gripping member and by the cradle-shaped end so as to lie flat, said member constituting a tear-off bar for severing the paper.

2. A memo roll holder comprising a sheet of material with integral and parallel side extensions projecting from its lower end, the portion of the sheet adjacent to the extensions being curved to provide a cradle and holder for a memo-roll, said extensions being shaped into scroll formations for acting as retaining members for the ends of the roll, said sheet having a flat portion extending from the curved end with a top that is inclined to the flat portion and lying in a plane that is tangent to the rear portion of the curved end, a paper gripping and guiding bar secured to the flat portion at its juncture with the top, whereby the writing portion of the paper is held in a taut position on the flat surface by the frictional engagement of the paper with the curved outer surface of the cradle and the gripping bar, said bar also constituting a tear-off bar.

3. In a device of the type described comprising a sheet of material having integral extensions, the material being curved adjacent to the extensions for receiving a memo roll, and the extensions being fashioned into scrolls for constituting end retaining members for the roll.
